DESIGN.

No. 32,175.

Patented Jan. 30, 1900.

G. W. REAM.

SHARE FOR PLOWS.

(Application filed Dec. 2, 1899.)

UNITED STATES PATENT OFFICE.

GEORGE W. REAM, OF CANTON, OHIO, ASSIGNOR TO THE BUCHER & GIBBS PLOW COMPANY, OF SAME PLACE.

DESIGN FOR A SHARE FOR PLOWS.

SPECIFICATION forming part of Design No. 32,175, dated January 30, 1900.

Application filed December 2, 1899. Serial No. 739,047. Term of patent 14 years.

To all whom it may concern:

Be it known that I, GEORGE W. REAM, a citizen of the United States, residing at Canton, in the county of Stark and State of Ohio, have invented and produced a new and original Design for a Share for Plows, of which the following is a specification.

In the accompanying drawings, Figure 1 is a plan view of a share embodying my design.

Fig. 2 is a view of the under face. Fig. 3 is a view looking directly at the point of the shoe in the direction of the arrow 1, Fig. 1. Fig. 4 represents a view from the direction of the arrow 2, Fig. 1. Figs. 5, 6, and 7 represent sections on lines A B, C D, and E F, Fig. 1.

The leading feature of the design is in the outline configuration of the share. The body A of the share is curved upwardly from the lower edge, this curve being greater toward the rear, as shown by the sectional views Figs. 5, 6, and 7. The lines a b, indicating the upper and lower edges of the body of the share, diverge slightly toward the point of the share,

to which the line b curves, as shown at c. 25 From the end d of the upper line an elongated compound-curved line e forms the edge of the share, leading to the point. From the edge e a vertical wall f of angular outline extends to form the bottom edge of the share. 30

Fig. 2 shows the under face of the share, while Fig. 3 shows the relative position of the parts from a front view.

The vertical wall is continuous from the compound-curved edge e. The upper surface 35 immediately in rear of the point inclines upwardly and merges gradually into the lateral incline of the main part of the share. The edge e and the edge at the opposite end of the share are at a decided angle to each other, diverging toward the front. 40

What I claim is—

The design for a plowshare as herein shown and described.

GEORGE W. REAM.
